[57] CLAIM

The ornamental design for a child's bib for motor skill development, as shown and described.

DESCRIPTION

FIG. 1 is an isometric view from the front, left side and top of a child's bib for motor skill development, showing my new design; and,

FIG. 2 is a reduced-scale isometric view from the rear, left side and top thereof.

1 Claim, 1 Drawing Sheet

FIG. 1

FIG. 2
